UNITED STATES PATENT OFFICE.

RUDOLF E. HELLMUND, OF SWISSVALE, PENNSYLVANIA, ASSIGNOR TO WESTINGHOUSE ELECTRIC & MANUFACTURING COMPANY, A CORPORATION OF PENNSYLVANIA.

RAILWAY MOTOR.

Application filed October 24, 1923. Serial No. 670,454.

To all whom it may concern:

Be it known that I, RUDOLF E. HELLMUND, a citizen of the United States, and a resident of Swissvale, in the county of Allegheny and State of Pennsylvania, have invented a new and useful Improvement in Railway Motors, of which the following is a specification.

My invention relates to electric railway 10 motors and has particular relation to bipolar-motor construction.

The introduction of the ventilated motor in railway service, and the experience met with during snow storms, makes a railway 15 motor having a minimum number of coils and other electrical parts, such as connecting leads which are subject to insulation breakdowns, especially desirable. It is also desirable to have such parts located as far away 20 from the bottom of the motor as possible.

A bipolar motor provided with two main field coils and a single commutating coil would serve to overcome the above difficulty but would normally require such large magnetic frame sections as would be too heavy to 25 employ for commercial railway operation.

The principal object of my invention is to provide a bipolar-railway-motor structure to overcome the above difficulty by having a heavy magnetic section carrying the major portion of the flux on the suspension side of the frame, opposite the railway axle, and having two small magnetic sections on 30 the axle side, the motor having two main pole pieces located respectively above and below the armature and a single commutating pole located on the suspension side.

Another object of my invention is to provide a railway motor wherein the gear-center distances will be reduced to a minimum, the railway axle being located partially within the interior of the motor frame, and means being provided for collecting and draining oil from the axle bearings.

A further object is to provide a railway-motor mounting that will provide a relatively large clearance space thereunder.

Other objects of my invention are to provide a compact, simple, practical and relatively inexpensive structure of the above class wherein the air inlet is located to the best advantage.

With the foregoing and other objects in view, my invention consists in the details 55 and combinations herein described and

claimed and illustrated in the accompanying drawing, wherein

Figure 1 is a view in transverse section through the motor, on the line I—I of Fig. 2, and

Fig. 2 is a view in longitudinal section through the frame thereof, on the line II—II of Fig. 1.

Referring to the drawing, the numeral 1 designates a wheel of a car truck mounted 65 upon an axle 2, and the numeral 3 designates a transverse motor-suspension bar carried by the truck.

The motor, which is geared to the axle 2 by the usual means, (not shown) is shown 70 as a commutator motor comprising an armature 4 mounted within suitable bearings at the ends of the frame 5 and operating between laminated pole pieces 6 carried, respectively, by the upper and lower walls 7 75 of the frame. The pole pieces are energized by coils 8 mounted thereon and are so disposed that the gap between the same and the side of the frame toward the wheel axle is less than that on the opposite or suspension 80 side. A laminated interpole piece 9 extends from the suspension side wall 10 of the frame and has a coil 11 disposed thereon.

The upper and lower walls 7 of the motor frame 5 gradually decrease in cross section 85 from the suspension side wall 10 toward the opposite side wall 10^a adjacent the car-wheel axle.

The frame is rigidly attached to the suspension bar 3 by its wall 10, which is a flat 90 plate of uniform thickness throughout, constituting a heavy magnetic section between the poles.

The wall 10^a of the frame, adjacent the car axle, is provided, at each end, with a 95 bearing bracket 12, having a cap 13 bolted thereto. The wall 10^a on the axle side is of lighter section than the wall 10 on the suspension side and comprises two portions 14 that terminate near the axle bearing to carry the magnetic flux near the axle, the opening 15 between the portions 14 preventing excessive flux leakage from the frame to the armature. The wall 10^a also carries a sheet-metal covering 16 which extends about the outer portion of the axle over the opening 15 to prevent the entry of dust or dirt to the frame.

To prevent the entry of oil from the axle 2 to the frame and consequent injury to the 110

lower field coil, an inwardly and upwardly extending lip 17 is provided at the lower part of the wall 14 to extend a sufficient distance over the coil to direct the oil out 5 through one or more drain openings 18.

An air inlet 19 is located in the wall 10* of the frame above the axle. To prevent the entrance of snow, a sheet-metal hopper-like cover 19*, open at the top, is attached 10 to the outside of the wall, also a plate 20 extends across the upper part of the inlet to cause the air to descend to the bottom of the inlet, as indicated by the arrows 20A and 20B in Fig. 1. A transversely disposed 15 bent plate 21 is secured within and across the inlet, leaving an open space 22 at one end thereof through which the air passes, in a horizontal direction, to the interior motor space adjacent the commutator, as 20 indicated by the arrow 22C in Fig. 2.

A suitable fan (not shown) may be located at the other end of the frame on the armature shaft to create a circulation of the air that enters the inlet opening 19.

25 While I have shown and described a certain embodiment of my invention, I desire that such embodiment shall be regarded as illustrative only, and that the appended claims shall be accorded the broadest construction consistent with the prior art.

I claim as my invention:

1. A bipolar railway motor comprising an armature and a field frame, the latter having two main pole members respectively located 35 above and below the armature, means for supporting a railway axle at one side of the frame, means for suspending the frame at the opposite side thereof, and a single commutating pole member located on the suspension side thereof.

2. A bipolar motor frame comprising a heavy magnetic section on the one side and two smaller sections on the opposite side.

3. A bipolar railway motor comprising a frame having a heavy magnetic section on the one side and two smaller sections on the opposite side and an opening between said smaller sections, and an axle disposed adjacent said two smaller sections.

50 4. A bipolar railway motor comprising an armature and a field frame, the latter having a heavy magnetic section on one side thereof, two smaller magnetic sections on the opposite side and a space therebetween, means 55 for suspending said frame at the first-mentioned side, car-wheel-axle bearings at said second-mentioned side, two main pole members respectively located above and below the armature, and a single commutating pole member located at the suspension side of 60 the frame.

5. A bipolar railway motor comprising an armature and a field frame, the latter hav-

ing a heavy magnetic section on one side thereof, two smaller magnetic sections on the opposite side and a space therebetween, means for suspending said frame at the first-mentioned side, and means for mounting a car-wheel axle adjacent said two smaller sections.

6. In combination with a railway motor frame, bearings adapted to support a railway-wheel axle projecting partially into the interior motor space, and means for collecting oil from the axle bearing and for discharging the same from the motor frame.

7. In combination with a railway motor frame, bearings adapted to support a railway-wheel axle and projecting partially into the interior of the motor frame, and means for dissymmetrically concentrating the weight of the motor toward the side opposite said axle.

8. In combination with a railway motor of the commutator type, means for mounting a railway-wheel axle adjacent one side of the motor, the motor frame having an opening above said axle, a baffle means for directing air downwardly toward said opening, and baffle means within said frame for directing the air horizontally toward the interior motor space near the commutator.

9. A railway motor comprising a frame having one side mounted adjacent a railway-wheel axle, an air inlet in said side of the frame above said axle, and means for directing the air downwardly toward said inlet and then transversely within said frame.

10. A bipolar railway motor comprising a frame having two main pole members, one located above and the other below, each provided with a coil, a single commutating pole member at one side thereof, and means at the other side for supporting a railway-wheel axle and for directing oil from the axle away from the lower coil.

11. A bipolar railway motor comprising a frame having a suspension means at one side and a railway-wheel axle at the other side, a heavy magnetic section at the suspension side thereof, a commutator pole member on said section provided with a coil, a pair of main pole members, one disposed at the top and the other at the bottom of the frame and each provided with a coil, said frame having two smaller magnetic sections disposed on the axle side thereof, with a space therebetween and having an air inlet above said axle, and means at said air inlet for directing the incoming air downwardly and then horizontally into said frame.

In testimony whereof, I have hereunto subscribed my name this 20th day of October, 1923.

RUDOLF E. HELLMUND.
